UNITED STATES PATENT OFFICE.

WILLIAM K. FRALEY, OF LEBANON, INDIANA, ASSIGNOR OF ONE-HALF TO
WILLIAM H. HOSTETTER, OF SAME PLACE.

WAGON-STANDARD.

SPECIFICATION forming part of Letters Patent No. 673,867, dated May 14, 1901.

Application filed November 19, 1900. Serial No. 36,931. (No model.)

To all whom it may concern:

Be it known that I, WILLIAM K. FRALEY, a citizen of the United States, residing at Lebanon, in the county of Boone and State 5 of Indiana, have invented a new and useful Wagon-Standard, of which the following is a specification.

My invention relates to an improvement in standards for lumber or box-bed wagons.

10 The object of my invention is to produce a wagon-standard of such form that it may be readily attached to bolsters of different thicknesses and of such form that a straight lengthening-stake may be used in connection therewith to form an extension, the inner face of which shall lie in the same plane as the inner face of the standard and without narrowing the available width of the wagon-bed.

15 The accompanying drawings illustrate my invention.

Figure 1 is a perspective view of a wagon-bolster provided with a pair of my improved standards, a lengthening-stake being placed in one of the standards. Fig. 2 is a sectional detail.

20 In the drawings, 4 indicates a bolster of the ordinary form, provided at each end with the usual stake-mortise 5.

25 My improved standard consists of right and left castings 6 and 7, which are complements one of the other. Each of these castings is provided upon its outside edge with an ear 8, having an elongated boss 9 formed upon its inner face, said boss being perforated by one or more bolt-holes 10. Each casting is also provided at its base with a foot 11, adapted to rest upon the upper face of the bolster, and a flange 12, which extends down alongside the bolster. Flange 12 is provided 30 with suitable bolt-holes, by means of which the two castings may be bolted upon the bolster, as shown. The upper ends of the castings are maintained a proper distance apart by means of a thimble 13, formed, preferably, of sheet metal. Thimble 13 is adapted to receive bosses 9 and to extend between the ears 8 to form a strut, bolts 14 passing through holes 10 and clamping the parts firmly together. The 35 length of the thimble 13 will be dependent upon the thickness of the bolster 4. In bolting the two castings 6 and 7 to the bolster

care should be taken that that portion in front of the thimble 13 should lie immediately above the mortise 5 for a purpose which will be made to appear. Under ordinary circumstances the inner edges of the castings 6 and 7 form a standard against which material may be piled. If it is desired to extend this standard, the operator has merely to use a stake 15, one dimension of which is equal to the distance between the adjacent faces of the castings and the other dimension of which is equal to the distance between the inner edges of said castings and the thimble 13, said stake being provided at its lower end with a tenon 60 adapted to enter the mortise 5. If desired, each casting 6 and 7 may be provided with a keyhole-opening 16, through which and a similar opening through a stake 15 may be passed a key 17, which, when it has been inserted may be allowed to turn so that its finger 18 will prevent an accidental withdrawal thereof.

It will be noticed that my standard is such that it may be easily fitted to any thickness 75 of bolster, and when provided with a thimble 13 of the proper length is rigid in position. A further advantage lies in the fact that a perfectly straight lengthening-stake 15 may be used, and that this lengthening-stake will 80 form a continuation of the inner face of the standard, so that the usual offset does not appear.

I claim as my invention—

1. A wagon-standard composed of a pair of 85 complementary pieces adapted to be secured to the bolster, a removable strut, and means for detachably securing said strut between the upper ends of said pieces at a point away from the working edges of said pieces, the arrangement being such that a lengthening-stake may be placed between said pieces so as to form a continuous edge thereto.

2. A wagon-standard composed of a pair of complementary sides adapted to be secured to the bolster, a detachable thimble, and means for clamping said thimble between the upper ends of said sides at a point away from the working edges of said pieces, the arrangement being such that a lengthening-stake may 95 be placed between said pieces so as to form a continuous edge thereto.

3. A wagon-standard composed of a pair of complementary sides each provided with a perforated boss 9 upon its adjacent face, a thimble 13 adapted to fit over and extend between said bosses, and a bolt for clamping said thimble between said sides.

4. The combination with the bolster having a mortise therein, of a three-sided or U-shaped standard secured to said bolster adjacent said

mortise, the arrangement being such that a lengthening-stake may be placed in said mortise and supported between the sides of said standard so as to form a continuous inner edge thereto.

WILLIAM K. FRALEY.
